UNITED STATES PATENT OFFICE.

STEPHEN E. HARBACK, OF FORT SMITH, ARKANSAS.

PNEUMATIC SCALE.

1,070,460.

Specification of Letters Patent. Patented Aug. 19, 1913.

Application filed June 17, 1911. Serial No. 633,892.

To all whom it may concern:

Be it known that I, STEPHEN E. HARBACK, a citizen of the United States, residing at Fort Smith, in the county of Sebastian and State of Arkansas, have invented a Pneumatic Scale, of which the following is a specification.

My invention relates to the weighing of merchandise on a scale actuated by some aeriform fluid, preferably air, instead of by a series of beams and weights, or springs, etc., supported on knife-edged bearings; and the objects of my invention are to make a scale, more durable, and, at the same time, more accurate. I attain these objects by the mechanism illustrated in the accompanying drawing, in which,

Figure 1 is a vertical section of the scale; Fig. 2 is a section in rear of the mechanism 20 of the scale; Fig. 3 is a front view of the charts; Fig. 4 is a detail in front of the piston.

Similar letters refer to similar parts throughout the several views.

25 The base *a*, in which is the valve *b*, and the port *c*; and the base-plate *d*, upon which are the perforated seats *e*; together with the cylinder *f*, which joins the base at *g*; serve to form a space about the cylinder and tubes 30 exhausted by means of valve *b*.

The platform *h*, extended downward about the base, as shown in Fig. 1, to protect the oil referred to hereinafter, from dust and cold, is supported on the wall *i*, which is ribbed vertically to engage the wheels *j*. These wheels are at the terminations inwardly of the head-plate of the cylinder, and prevent the shifting of the platform when it is loaded. The platform *h*, and the wall *i*, are superimposed on the piston *k*. This piston *k* is double-plated, and the space between the plates exhausted by means of the valve *l*. These plates are set within, and at the top of, a continuous band 45 having two diameters, see Fig. 4, at neither of which does the band touch the cylinder. A lower plate is fixed within the band at the junction of the two diameters. This third plate is open in the center for the passage of the barrel of a lifting pump, and serves, with the band *m*, see Figs. 1 and 4, at this level perforated, to form the reservoir *n*, which holds a body of some suitable oil. Cut in the face of the band next to 50 the cylinder and on the greater diameter, where the band has a ridge, is a helical

groove, the lowest turn of which is on a plane with the ridge, and which carries a spring corresponding to it. Any system of use of piston packing rings may be substituted for the spring. I prefer the spring described. It bears on the walls of the cylinder with a strength less than the gravity of the piston with its superstructure. Through the perforations in the band the oil of the reservoir *n*, flows to the vestibule, formed by the difference in the diameters of the band, see Fig. 4, whence it fills up the spaces about the spring and seals the air within the cylinder and tubes. 60

Escapements of oil below the piston find their way to the bottom of the cylinder, and into the cistern at the center of it, see Fig. 1. The barrel of a lifting pump *o*, having a continuous spill-way overhanging the rim of the reservoir, enters the cistern. The pump-rod is fast to the under-plate of the piston. Both plates of the piston, as well as the bottom-plate of the cylinder, are made to accommodate themselves in shape to the working of the pump, which, when the scale is in action, brings oil from the cistern to the reservoir, and a circulation of the oil is sustained. 70

Extending outward and upward from the main-port *p* is the transmitting tube *q*, intersected in its length by the barometric tube *r*, see Fig. 2. These tubes are closed with snugly fitting pistons of a different weight one from the other, and each piston is confined to a given path by stops in the tube. The tubes, with their pistons, may be used similarly, for purposes of indication. I prefer a sealed barometric tube, as shown by *r*, Fig. 2. To the outer end of the tube *q* is 80 suitably fixed a Bourdon pressure gage tube *s*.

Now if air be pumped into the cylinder and tubes by means of the valve in the cylinder at *c*, the weights of the two pistons in the tubes, taken together, will counterpoise the piston in the cylinder together with its superstructure. The varying barometric pressures on the platform will cause the piston in the tube *r* to rise and fall in the 90 tube, because this piston is lighter than that in the tube *q*, and will be the first to register extraneous influences on the confined air. An even pressure is therefore maintained throughout the air in the cylinder and tubes. Place merchandise on the platform. An impulse is sent through the confined air, shown 100

by an added movement of the piston in the tube *r*. But the piston in the tube *q* will now move, and compress the air in the Bourdon tube *s*, which will tend to straighten, and move the indicating mechanism attached to it.

The adjustable, pivoted lever *t*, Fig. 2, toothed at one end to engage the teeth on the wheel *u*, is connected at the other end 10 to the Bourdon tube *s*. On one side of the wheel *u* is attached a circular chart, the face of which is partially masked. It is graduated in pounds and ounces, in sections; and from a section line is read the fixed crown-15 chart *v*, also drawn in pounds and ounces, and showing computations in dollars and cents, all in multi-colored lines.

Those parts of the scale above the base *a* 20 are sheathed in the framework *w*, the space within which is exhausted through perforations in the base by means of the valve *b*.

I claim in a pneumatic scale:

1. In a scale for registering weight, a platform, an air chamber, a hollow piston 25 therefor arranged to hold a fluid and provided with outlets for permitting the flow of fluid to close the space between the piston and the walls of the air chamber, and means actuated by the air pressure within the 30 chamber for registering weight of a body on the platform.

2. In a scale for registering weight, a platform, an air chamber, a hollow piston 35 therefor arranged to hold a fluid and provided with outlets for permitting the flow of fluid to close the space between the piston and the walls of the air chamber, a Bourdon tube having communication with the interior of the air chamber, and means operated by

the Bourdon tube for registering the weight 40 of a body on the platform.

3. In a scale for registering weight, a platform, an air chamber, a hollow piston therefor arranged to hold a fluid and provided with outlets for permitting the flow of 45 fluid to close the space between the piston and the walls of the air chamber, a well in the bottom of said air chamber for receiving fluid which escapes between the piston and the walls of the air chamber, means operated 50 by the movement of the piston for returning the fluid to the interior of the piston, and means actuated by the air pressure within the chamber for registering the weight of a body on the platform. 55

4. In a scale for registering weight, a platform, an air chamber, a hollow piston therefor arranged to hold a fluid and provided with outlets for permitting the flow 60 of fluid to close the space between the piston and the walls of the air chamber, a well in the bottom of said air chamber for receiving fluid which escapes between the piston and the walls of the air chamber, means operated 65 by the movement of the piston for returning the fluid to the interior of the piston, means actuated by the air pressure within the chamber for registering the weight of a body on the platform, said means comprising a Bourdon tube having communication 70 with the interior of the air chamber, and a registering device operated by said Bourdon tube.

STEPHEN E. HARBACK.
